LABORATORY POTENTIOMETER

Gale E. Boulton, 13771 Olympic Ave., Costa Mesa, Calif.

Filed May 5, 1964, Ser. No. 79,815

Term of patent 14 years

(Cl. D26—1)

FIGURE 1 is a left side, top and front perspective view of a laboratory potentiometer, showing my new design; FIGURE 2 is a top plan view, to a reduced scale;

FIGURE 3 is a front elevational view, to a reduced scale;

FIGURE 4 is a left side elevational view, to a reduced scale, the right side being substantially a mirror image thereof; and

FIGURE 5 is a rear elevational view thereof, to a reduced scale.

Diagonally lined areas in elliptical areas of the drawings represent transparent portions.

I claim:

The ornamental design for a laboratory potentiometer, substantially as shown and described.
